UNITED STATES PATENT OFFICE.

JOHN HELLINGS, OF PHILADELPHIA, PENNSYLVANIA.

MECHANICAL MOVEMENT.

SPECIFICATION forming part of Letters Patent No. 430,852, dated June 24, 1890.

Application filed October 4, 1889. Serial No. 326,014. (No model.)

To all whom it may concern:

Be it known that I, JOHN HELLINGS, a citizen of the United States, and a resident of Philadelphia, Pennsylvania, have invented

5 certain Improvements in Mechanical Movements, of which the following is a specification.

The object of my invention is to construct an improved mechanical movement by which 10 weights of varying character may be raised or lowered.

I have shown in the drawings my invention adapted to a coal-wagon and a box-lifting device; but it will be understood at the 15 outset that it is capable of application to a number of other devices for raising and lowering weights.

In the accompanying drawings, Figure 1 is a perspective view of my improved mechanical movement. Fig. 2 is a longitudinal section of the device lowered. Fig. 3 is a longitudinal section of the device raised. Fig. 4 is a side view of a coal-wagon, showing my improved mechanical movement applied thereto. Fig. 5 is a view of a box-lifting device embodying my invention. Figs. 6 and 20 7 are views showing the construction of my device when used in connection with the box-lifter, Fig. 5; and Fig. 8 is a view of a modification.

Referring to Figs. 1, 2, and 3 of the drawings, A is a frame having undercut guideways a a, in which slide the tongues b of the slide B.

35 D is a rod or shaft on which are cut two threads, one a right-hand thread and one a left-hand thread. The rod or shaft D passes through a lug c on the frame A and through a lug d on the slide B. The right threaded portion of the rod is adapted to the lug c, and the left threaded portion is adapted to the lug d on the slide B, so that on the turning of the screw-rod the slide will be moved longitudinally in respect to the frame.

40 The frame in many cases will be mounted upon a bed E, and the end of the screw-shaft or rod D will be mounted in bearings in this bed, the frame sliding upon the bed, as indicated, so that when the shaft is turned the 45 two parts A and B will be moved toward or from each other.

The slide B has an inclined way B', on the

inclined surface of which rolls a flanged roller F, mounted on a shaft G, adapted to bearings on two links or arms H H, pivoted at h 55 to the frame A.

On the shaft G is a supporting-frame I. In the present instance this supporting-frame is pivoted to the shaft and pivoted in two bearings J J, so as to rock transversely. The 60 bearings are secured to and support the device to be lifted, so that it will be seen that as the screw-rod is turned, and as the two parts A and B come together, the roller F will be forced up the inclined plane B' from the 65 position shown in Fig. 2 to that shown in Fig. 3, thus raising any article or device that may be placed upon it. In Fig. 4 I have shown this mechanical movement as applied to dumping-carts, the bearings J J being secured to 70 the body M of the dumping-cart, so as to lift the said body a sufficient height to allow the contents of the cart to be dumped through the opening m, and if the contents are to be dumped through one of the side openings m', 75 for instance, the frame is tilted transversely, and the bearings of the frame I, which are mounted on the blocks J J, become the turning-points.

Suitable locking devices are secured to the 80 rear or front portions of the cart to prevent the body from tilting when it is not required. By simply holding the rear end of the cart while the device is turned to raise the cart the body will be raised to an angle sufficient 85 to allow the contents to be dumped.

In Fig. 5 I have shown my improved mechanical movement mounted on a truck N, the truck having a standard N', and on the under side of the frame A is a pin a', adapted 90 to an opening in the standard and acting as a pivot, so that the frame A can be turned independent of the truck. The links H in this instance are extended, forming a gripping-frame H', thus dispensing with the frame 95 I and bearing-blocks J, and on the lower end of the frame H' is a lip i and on the upper portion of the frame is a shaft j, having a drum on which is wound a cord or chain k, having at its outer end a gripping-hook k'. 100 The shaft is provided with a handle j'.

A box, for instance, is mounted on the truck, and if it is wished to lift the box a certain height to place it upon a wagon, for in-

stance, the box W is moved so as to pass over the lip *i* on the lower portion of the frame H', and the hook *k'* is placed, as shown, at the opposite edge of the box and the rope 5 pulled taut, after which the shaft D is turned by a suitable handle *d'* and the box raised from the position shown by full lines in Fig. 5 to that shown in dotted lines in said figure. In this instance the frame A does not slide 10 on a supporting-bed, as shown in Fig. 1, the slide B being the only moving part. This is not an objection, as it only changes the vertical lifting line, which is on a vertical line in Fig. 1, while in Fig. 5 the lift is in the arc of a 15 circle.

Figs. 6 and 7 show details of the construction shown in Fig. 5.

In some instances the inclined way may be reduced, as shown in Fig. 8, and above this 20 inclined way I pivot a link B², having an open jaw *b'*, into which the roller passes when it reaches the limit of the incline, and as the movement of the roller continues the link B² is raised until the limit is reached. This arrangement I may use when it is required that the article lifted shall be as near the base as possible without cutting in the bottom of said article to allow for the passage of the inclined way—such, for instance, as dumping 25 wagons or carts.

The mechanical movement may be applied to lifting-jacks, presses, and other devices where great power is required.

It will be understood that instead of the slide 35 carrying the inclined way and the frame carrying the links or arms the frame may be provided with the inclined way and the slide carry the links or arms, although I prefer to use the construction shown in Fig. 1. The 40 links or arms H have side extensions *f*, which rest upon the frame, taking the strain off the pivot-pins, as clearly shown in Fig. 1.

It will be understood that in some instances the roller F may be dispensed with, and its 45 shaft G would then rest on the inclined slide-way, although a non-rotating block may be used instead of the roller without departing from my invention.

I claim as my invention—

50 1. The combination of the frame A, the slide B, with a screw-shaft adapted to draw the slide upon the frame, with an inclined way mounted on one of the parts and with links pivoted to the other part, and a shaft having 55 a roller adapted to the way, so that on the

turning of the screw-shaft the roller will be moved up or down upon the inclined way, substantially as described.

2. In a mechanical movement, the combination of the frame A, a slide B, having an inclined way, with links pivoted to said frame A, and a shaft having a roller adapted to said inclined way with a screw-shaft for moving the slide on the frame, so that on the movement of the slide the roller will be moved up 60 or down the inclined plane, substantially as described.

3. The combination, in a mechanical movement, of the frame, a slide adapted to said frame, an inclined way on said slide, pivoted 70 links, and a shaft carrying a roller with a screw-shaft having right and left hand screw-threads, one of said screw-threads adapted to the frame, the other adapted to the slide, substantially as described.

4. The combination of the bed E, frame adapted to slide thereon, with a slide adapted to ways on the frame, an inclined way carried by said slide, with links pivoted to said frame and carrying at their upper ends a 80 roller, with a screw-shaft having a right and a left hand thread thereon, one thread adapted to the frame and the other adapted to the slide, said shaft fixed as regards longitudinal movement in the bed E, so that on the turning 85 of said shaft the slide and frame will be moved, substantially as described.

5. The combination of the frame, slide thereon having inclined ways, a shaft having a roller adapted to said ways and connected 90 by links to the frame, with a frame I, pivoted to the shaft of the roller, and the said frame being pivoted to blocks J J, so that the device mounted on said blocks can be longitudinally and transversely tilted, substantially as de- 95 scribed.

6. The combination of the frame, the slide adapted thereto, an inclined way on said slide, a link pivoted to said way and having a jaw, with links pivoted to said frame, and a shaft 100 carrying a roller, the whole acting substantially as described.

In testimony whereof I have signed my name to this specification in the presence of two subscribing witnesses.

JOHN HELLINGS.
